UNITED STATES PATENT OFFICE.

JESSE B. MARSHALL AND LEWIS Y. McCLURE, OF WOOSTER, OHIO.

DESIGN FOR A HITCHING-POST.

SPECIFICATION forming part of Design No. 25,069, dated January 21, 1896.

Application filed August 10, 1895. Serial No. 558,947. Term of patent 7 years.

To all whom it may concern:

Be it known that we, JESSE B. MARSHALL and LEWIS Y. McCLURE, citizens of the United States, residing at Wooster, in the county of Wayne and State of Ohio, have invented and produced an original Design for a Hitching-Post, of which the following is a specification.

Our invention relates to a design for hitching-posts.

The drawing shows in perspective a hitching-post embodying our design.

1 indicates the circular shaft or body portion.

3 indicates the circular base curved at 2, as shown.

4 indicates an enlarged bulb-shaped cap-piece surmounting the shaft or body portion, and 9 indicates a hook-shaped extension having a circular base 10 surmounting the post 4.

We claim—

The design for a hitching post substantially as shown and described.

In testimony whereof we affix our signatures in presence of two witnesses.

JESSE B. MARSHALL.
LEWIS Y. McCLURE.
